UNITED STATES PATENT OFFICE

117,254

DESIGN FOR AN ICE TRAY

Clifford R. Carney, Detroit, Mich.

Application September 2, 1939, Serial No. 87,013

Term of patent 14 years

To all whom it may concern:

Be it known that I, Clifford R. Carney, a citizen of the United States, residing at Detroit, Wayne County, Michigan, have invented a new, original, and ornamental Design for an Ice Tray, of which the following is a specification, reference being had thereto to the accompanying drawing, forming a part thereof, in which

Fig. 1 is a view in perspective of the ice tray showing my design;

Fig. 2 is a side elevational view thereof;

Fig. 3 is an end elevational view thereof; and Fig. 4 is a cross-sectional view taken substantially on the line 4—4 of Fig. 1.

The dominant feature of the design resides in the grid portion shown in full lines.

I claim:

The ornamental design for an ice tray, substantially as shown and described.

CLIFFORD R. CARNEY.
